UNITED STATES PATENT OFFICE.

FRANK WILLIAM LEV, OF NEW YORK, N. Y., ASSIGNOR TO C. & L. MACHINE COMPANY,
OF ASTORIA, NEW YORK, A CORPORATION OF NEW YORK.

PACKAGING-MACHINE.

1,218,786.

Specification of Letters Patent. Patented Mar. 13, 1917.

Application filed May 12, 1914, Serial No. 838,090. Renewed March 18, 1915. Serial No. 15,385.

To all whom it may concern:

Be it known that I, FRANK WILLIAM LEV, a citizen of Austria, and a resident of the borough of Queens, city of New York, in the

5 county of Queens and State of New York, have invented certain new and useful Improvements in Packaging-Machines, of which the following is a specification.

This invention relates to machines in 10 which articles are placed in a magazine and several of said articles separated therefrom are compressed into a compact bunch, and, together with a wrapper are forced through the machine, said machine having wrapper 15 folding and paste applying means, whereby the wrapper is folded and secured upon the articles, thereby forming a package.

The object of the invention is to provide means whereby part of the operation of folding of the wrapper can be performed by one set of mechanism which is distinct from a set of mechanism performing the operation of folding of another part, whereby the machine can by suitable adjusting means, be 25 changed from one working automatically into one which can be manually operated.

One set of mechanism actuates a plunger, the movement of said plunger serving to actuate mechanism for separating articles 30 from the magazine and compressing them into a compact bunch, said plunger then forcing said articles and a wrapper through a wrapper folding channel. This set of mechanism also actuates a paste applying mechanism during travel of said articles and 35 wrapper through said wrapper folding channel. This set of mechanism also actuates a plunger the movement of which is in time with the first named plunger.

40 The other set of mechanism actuates another plunger the movement of which actuates movable folders of the wrapper, said plunger also actuating movable walls thereby permitting said plunger to force said 45 articles and wrapper through another wrapper folding channel. This set of mechanism also actuates another paste applying mechanism during travel of said articles and wrapper through the last named wrapper 50 folding channel. This set of mechanism also actuates a shaker having reciprocating movements in said magazine.

Means are provided whereby these two 55 sets of mechanism are actuated automatically, and adjustable means provided for

disconnecting said automatic means, whereby each one of said sets of mechanism can be manually operated levers be independently operated.

In the accompanying drawings:

60

Figure 1 is a plan view of the machine.

Fig. 2 is a detail drawing of the magazine, showing partitions for separating articles therefrom.

Fig. 3 is a view similar to Fig. 1, showing 65 movable parts in a different position.

Fig. 4 is a view similar to Fig 2, showing the separating partitions moved closer together.

Fig. 5 is an enlarged longitudinal section on the line V—V of Fig. 1.

Fig. 6 is a transverse section on the line VI—VI of Fig. 5.

Fig. 7 is a transverse section on the line VII—VII of Fig. 5, showing movable parts 75 in a different position.

Fig. 8 is a front elevation of the machine, a part being shown in section on the line VIII—VIII of Fig. 1.

Fig. 9 is a detail section on the line 80 IX—IX of Fig. 1.

Fig. 10 is an enlarged view of mechanism for actuating the paste applying device.

Fig. 11 is a transverse section on the line XI—XI of Fig. 8, showing part of one set 85 of mechanism adjusted for operation by a manually operated lever.

Figs. 12 and 13 are perspective views showing certain stages of folding of a wrapper upon the articles that are performed by 90 one of said sets of mechanism.

Fig. 14 is a transverse section on the line XIV—XIV of Fig. 1.

Fig. 15 is a transverse section on the line XV—XV of Fig. 3.

95

Figs. 16, 17, 18 and 19 are perspective views showing certain stages of folding of said wrapper upon the articles that are performed by the second set of mechanism.

Fig. 20 is a plan view of the machine, 100 showing independent operation of each one of said sets of mechanism.

Projecting upward from the frame 1 of the machine is a stud 2 upon which is journaled a gear segment 3 having oscillating 105 movement. Gear segment 3 is in mesh with a pinion 4 which is journaled upon a stud 5.

Secured to pinion 4 is a gear wheel 6 which is in mesh with a rack 7 formed on a plunger 8. Oscillating movements of gear 110

segment 3 and consequent movements of the gears 4 and 6 cause reciprocating movements of plunger 8 in guides 9. Plunger 8 is cut away at 10, so that when the plunger 8 occupies the position shown in Figs. 1 and 5, upward movement of one end of a lever 11 carrying a roller 12, will be permitted. Lever 11 is pivoted at 13, and the other end thereof is connected at 14 to one end of a lever 15 which is pivoted at 16. The other end of lever 15 is provided with a roller 17 which bears upon the upper end of a rod 18 having vertical movement in a guide 19. The lower end of rod 18 is provided with an arm 20 which bears upon a slide 21 having vertical movement in guides 22. Two links 23 which are inclined in opposite directions are pivoted at 24 upon the slide 21. Links 23 are also pivoted at 25 to the free ends of arms 26 which are journaled upon the fixed pivots 27. Also connected to the pivots 25 are slides 28 which have movements in guides 29. Forming part of slides 28 are vertical walls 30 and horizontal plates 31 which partially support articles placed in the magazine 32. By means of springs 33 acting against the two arms 26 the pivots 25 are moved away from the pivot 24 to which the links 23 are connected, thereby causing upward movement of slide 21 and rod 18, resulting in movement of levers 15 and 11 and consequent travel of roller 12 into said cutaway portion 10 of the plunger 8. In the space 35 between the vertical walls 30, are arranged partition plates 34. Secured to the ends of each one of the partition plates 34 are angularly shaped plates 35, which are provided with ends 36 interlocking with similar ends 36 of plates 35 secured to two adjacent partition plates 34, or to wall 30. A limited amount of play of an end 36 of one plate 35 is permitted between the end 36 of another plate 35 and that part of the last 40 named plate 35 which is secured to the partition plate 34. Accordingly when the walls 30 are separated to the distance shown in Fig. 6, the interlocking ends 36 of the plate 35 which is secured to each wall 30 will have 45 taken against the interlocking ends 36 of the plate 35 which is secured to an adjacent partition plate 34, and the other interlocking ends 36 of the latter plate 35 will have taken against the interlocking ends 36 of the plate 35 which is secured to another adjacent partition plate 34, and so on until all 50 of the partition plates 34 will have reached the limit of their travel, causing them to be separated equal distances apart as shown in Fig. 6. When the partition plates 34 are separated as shown in Fig. 6, the articles 37 readily enter the space between said partitions and come to rest upon the floor 38.

When plunger 8 moves forward, an incline 39 formed thereon takes against roller

12, thereby causing levers 11 and 15 to be actuated, resulting in downward movement of rod 18, arm 20, and slide 21; causing the links 23 to move the slides 28 and attached vertical walls 30, inwardly as shown in Fig. 7. It will be readily understood that the articles 37 and partitions 34 will then be brought closer together.

The plunger 8 is provided with slots 40, so that as forward movement of the plunger 75 moves the articles forward, the partitions 34 will enter the slots 40 and thus permit free travel of the plunger.

By suitable means, (not shown) a wrapper 41 of greater width than the space between the walls 30 shown in Fig. 7 is brought to rest on a support 42, in a vertical chute 43.

Forward movement of plunger 8 forces the articles 37 through a channel 44, thereby 85 causing said articles to force said wrapper between an upper plate 45, a lower plate 46 and two side folders 47; whereby said wrapper is folded upon the article in the manner shown in Fig. 12. Further forward movement of the plunger 8, causes upper side flap 48 of the wrapper to be turned down by means of folders 49, projecting downward from said upper plate 45. These folders 49 consists of plates which extend vertically 95 downward and are so placed that all of their inner surfaces are in line with the inner ends of the side folders 47. The wrapper folding operation is performed by means of the lower edges of the vertical plates, which 100 edges have a downward inclination of 20° from the upper plate 45. It will be seen that as these folders act only in line with the sides of the bunch of cigarettes, they serve to hold the cigarettes in place, and also to 105 make a sharp fold of the wrapper. In folders of this kind as heretofore constructed, the outer tips of the wrapper flaps were first turned down by means of curved surfaces, leaving the actual fold to be made as the article and wrapper were moved farther along the wrapper folding channel. It will be seen that my folders turn the flaps in line with the sides of the bunch of cigarettes, and that the tips of the wrapper flaps are the last 115 part that are reached by the folders.

The inner ends of side folders 47 extend back so that space only for passage of the wrapper flaps 48 is left between them and the inclined edges of folders 49. Consequently the cigarettes are held in place during their travel while the flaps 48 are being folded. Further forward movement of plunger 8 causes the cigarettes and down turned flaps 48 to travel next to downwardly 125 extending plates in line with folders 49, and causes lower side flaps 50 of the wrapper to pass under paste applying wheels 51, which wheels are rotated in the same direction as that in which said flaps 50 are traveling. 130

whereby paste 52 is deposited upon said flaps as shown in Fig. 13. The upper side of each wheel 51 travels in a paste receptacle 53, so that as the wheel rotates, it carries 5 paste out therefrom which paste is carried down and deposited upon said flap 52 in the manner described. Each wheel 51 is secured to a shaft 54 to which is secured a gear wheel 55. Gear wheels 55 are in mesh with gear 10 wheels 56 which are secured to a shaft 57. Loosely mounted upon shaft 57 is a gear wheel 58 which is in mesh with a rack bar 59 having reciprocating movement in guides 60. Pivoted upon gear wheel 58 is a spring 15 pressed pawl 61 adapted for engagement with a ratchet wheel 62 which is secured to shaft 57. Rack bar 59 is connected by a link 63 to the gear segment 3, so that, as the gear segment is moved in a direction to cause forward movement of plunger 8, the rack bar 20 will cause rotation of gear wheel 58 in such direction that the pawl 61 pivoted thereon will cause rotation of the ratchet wheel 62, and consequent rotation of the shaft 57, and 25 gears 56. It will be readily seen that rotation of gears 56 will cause rotation of gears 55, shafts 54 and paste applying wheels 51, in the same direction as that in which the wrapper flaps 50 are moved by forward 30 movement of plunger 8. Further forward movement of plunger 8 causes said paste coated lower side flaps 50 to be turned up by means of folders 64 projecting upward from said lower plate 46, thereby causing 35 said paste coated flaps 50 to be folded against the downwardly folded flaps 48. The folders 64 are constructed in the same manner as folders 49 with the exception that their upper edges are inclined upward from 40 the lower plate 46. The downwardly extending plates in line with folders 49 extend back so that space only for passage of the wrapper flaps 50 is left between them and the inclined edges of folders in order that 45 the cigarettes will be held in place during their travel while the flaps 50 are being folded. At the end of forward movement of plunger 8, said articles and partially folded wrapper are forced into a receiving chamber 50 55 having vertically reciprocating side walls 66 as shown in Figs. 3 and 15. Then as gear segment 3 is moved in a direction to cause return movement of plunger 8, the connection 63 will cause movement of rack bar 59 55 in a direction to cause rotation of gear wheel 58 in such direction that the spring pressed pawl pivoted thereon will ride over, and consequently have no effect upon the ratchet wheel 62. 60 Upon a stud 67 is journaled a gear segment 68 having oscillating movement. Gear segment 68 is in mesh with a pinion 69 which is journaled upon a stud 70. Secured to pinion 69 is a gear wheel 71 which is in 65 mesh with a rack 72 formed on a plunger 73. Oscillating movement of gear segment 68 and consequent movement of the gears 69 and 71 causes reciprocating movement of plunger 73 in guides 74. Plunger 73 is provided with a shoulder 75, so that when the 70 plunger 73 occupies the position shown in Figs. 3 and 15, said shoulder 75 having engaged a shoulder 76 forming part of a slide 77, has moved said slide to the position shown. Slide 77 and another slide 75 78 have reciprocating movement in guides 79. Each one of said slides is provided with a rack 80 which is in mesh with a pinion 81 placed between them, so that movement of one slide in one direction will by means of 80 said pinion, cause movement of the other slide in the opposite direction. Slide 77 is provided with a folder 82, and slide 78 is provided with a folder 83, said folders being in range with that part of the wrapper 85 which extends rearwardly from the articles within the wrapper, as shown in Fig. 16. When plunger 73 moves forward, causing the shoulder 75 to be moved away from the shoulder 76, a spring 84 acting on slide 78 90 causes the folders 82 and 83 to move toward each other. These movements of folders 82 and 83 cause the rearwardly extending portions of the wrapper flaps 48 and 50 to be turned inwardly as shown in Fig. 17. 95

The side walls 66 of receiving chamber 65 are secured to a cross bar 85 which is secured to a vertical rod 86 having reciprocating movement in a guide 87. A spring 88 between guide 87 and cross bar 85 forces 100 the cross bar downward, causing the side walls 66 to occupy the position shown in Fig. 15. One end of a lever 89 pivoted at 90 is connected to the upper end of rod 86, the other end of said lever being connected 105 by a link 91 to the free end of an arm 92 which is pivoted at 93. The free end of arm 92 is provided with an extension 94 which extends into range with a bar 95 secured to the underside of plunger 73. Bar 95 is 110 provided with an incline 96 which is adapted for engagement with extension 94 when plunger 73 continues its forward movement, thereby causing downward movement of arm 92, and by means of link 91, lever 89, rod 86 115 and cross bar 85, causing upward movement of the side walls 66. Further forward movement of plunger 73 then forces said partially wrapped articles out of said receiving chamber 65, and causes upper end flaps 97 120 of the wrapper to be turned down by means of downwardly projecting folders 98. Further forward movement of plunger 73 causes lower end flaps 99 of the wrapper to pass under a paste applying wheel 100, which is 125 rotated in the same direction as that in which said flap 99 is traveling, whereby paste 101 is deposited upon said flap, as shown in Fig. 18. The upper side of wheel 100 travels in a paste receptacle 102, carry- 130

ing paste out therefrom which is deposited upon the flap 99. Wheel 100 is secured to a shaft 103 to which is secured a gear wheel 104. Gear wheel 104 is in mesh with a gear wheel 105 which is secured to a shaft 106. Loosely mounted upon shaft 106 is a gear wheel 107 which is in mesh with a rack bar 108 having reciprocating movement in guides 109. Pivoted upon gear wheel 107 is a spring pressed pawl 110 adapted for engagement with a ratchet wheel 111 which is secured to shaft 106. Rack bar 108 is connected by a link 112 to the gear segment 68, so that, as the gear segment is moved in a direction to cause forward movement of plunger 73 the rack bar 108 will cause rotation of gear wheel 107 in such direction that the pawl 110 pivoted thereon will cause rotation of ratchet wheel 111, the gear wheel 105, and consequent rotation of gear wheel 104 and paste applying wheel 100 in the same direction as that in which the wrapper flap 99 is moved by forward movement of plunger 73. Further forward movement of plunger 73 causes said paste coated lower end flap 99 to be turned up by means of upwardly projecting folder 113, thereby causing said paste coated end flap 99 to be folded against the downwardly folded end flap 97. The folder 83 is shaped to extend near to the inclined edge of downwardly extending folder 98, and the plate in line with folder 98 is shaped to extend near to the inclined edge of upwardly extending folder 113; for purposes similar to those referred to in the description of folders 47, 49 and 64. At the end of forward movement of plunger 73, said articles and completely folded wrapper are forced into a receiving chamber 114, in range with a plunger 115.

Plunger 115 is connected by a link 116 to one end of a lever 117 which is pivoted at 118. The other end of lever 117 is connected by a link 119 to the gear segment 3, so that as the gear segment is moved in a direction to cause forward movement of plunger 8, forward movement will also be imparted to plunger 115, whereby said wrapped articles will be forced into a receiving channel 120. When plunger 115 moves out of the receiving channel, a spring catch 121 moves up to hold the wrapped articles in place.

In mesh with gear wheel 107 is a gear wheel 122 which is secured to a shaft 123. Shaft 123 is provided with a crank 124 which is connected by a link 125 to a shaker 126 having reciprocating movement in guides 127 formed in the magazine 32. The shaker 126 is provided with vertical walls 128 which move the articles into the spaces between said partitions 34.

The hub 129 of gear segment 3 is provided with teeth 130 adapted for engagement with corresponding recesses 131 of a

sliding clutch collar 132 which is journaled upon the stud 2. Forming part of clutch collar 132 is a gear segment 133 which is in mesh with a rack 134 forming part of a yoke 135, having reciprocating movement in guides 136. Yoke 135 is actuated by means of an eccentric 137 which is secured to a shaft 138. To shaft 138 is secured a gear wheel 139 which is in mesh with a smaller gear wheel 140 secured to a driving shaft 141.

Secured to shaft 138 is a cam 142 which actuates a yoke 143 having reciprocating movement in guides 144. Forming part of yoke 143 is a rack 145 which is in mesh with a gear segment 146 forming part of a sliding collar 147 which is journaled upon the stud 67. Collar 147 is provided with recesses 148 adapted for clutch engagement with corresponding teeth 149 formed on the hub 150 of gear segment 68.

The shape of cam 142 compared to that of eccentric 137 is such that, for example, the plunger 73 will be held in the position shown in Fig. 3, by means of mechanism actuated by cam 142, during the time that return movement is imparted to plunger 8 by means of mechanism which is actuated by eccentric 137.

Each one of the clutch collars 132 and 147 is provided with a groove 151 which is engaged by an arm 152 secured to a rock shaft 153. Rock shaft 153 is journaled in bearings 154 and is actuated by means of a lever 155 secured thereto, whereby said arms 152 cause the clutch collars 132 and 147 to be thrown into or out of engagement with the hubs of gear segments 3 and 68. By means of pin 156 engaging said lever and a hole formed in a standard 157, as shown in Figs. 1, 8 and 14, the clutch collars can be held in engagement with said hubs of the gear segments.

As shown in Figs. 11 and 20, the pin 156 engages said lever and the hole formed in standard 157 in a manner to hold the clutch collars out of engagement with said hubs of the gear segments.

Each one of the hubs 129 and 150 is provided with a squared portion 158 adapted to fit a correspondingly shaped recess 159 formed on a lever 160.

The mode of operation when manually operated as shown in Fig. 20 differs from that when operated by means of the eccentric 137 and cam 142, only in the loss of time which is required for complete return movement of one plunger before forward movement is imparted to the other plunger.

Having described the invention, what I claim is:

1. A packaging machine comprising a magazine for articles, said magazine having movable partitions, means for actuating said movable partitions whereby they are

separated sufficient distances apart to permit entry of several of said articles, a wrapper folding channel and a receiving chamber on one side of said magazine, and a reciprocating plunger on the opposite side, a support for a wrapper between said wrapper folding channel and said magazine, means for actuating said plunger, said means for actuating said movable partitions being actuated by said plunger, whereby forward movement of the plunger causes the partitions to be brought closer together, thereby causing said several articles to be forced into a compact bunch, further forward movement of said plunger then causing said articles and wrapper to be forced through said wrapper folding channel and into said receiving chamber, whereby the wrapper is partially folded upon said articles; a second wrapper folding channel in range with said receiving chamber, and a second plunger having reciprocating movements through said receiving chamber and said second wrapper folding channel; wrapper folders having reciprocating movements across the path of the first named plunger, said wrapper folders being actuated by said second plunger; means for actuating said second plunger, whereby said wrapper folders are actuated, thereby causing the wrapper to be further folded upon said articles, further forward movement of said second plunger then causing said partially wrapped articles to be forced into said second wrapper folding channel, thereby causing said wrapper to be completely folded upon said articles.

2. A packaging machine comprising a magazine for articles, said magazine having movable partitions, means for actuating said movable partitions whereby they are separated sufficient distances apart to permit entry of several of said articles, a wrapper folding channel on one side of said magazine and a reciprocating plunger on the opposite side, a support for a wrapper between said wrapper folding channel and said magazine; means for actuating said plunger, said means for actuating said movable partitions being actuated by said plunger, whereby forward movement of the plunger causes the partitions to be brought closer together, thereby causing said several articles to be forced into a compact bunch, further forward movement of said plunger then causing said articles and wrapper to be forced through said wrapper folding channel, whereby the wrapper is partially folded upon said articles; a second wrapper folding channel in range with said receiving chamber, and a second plunger having reciprocating movements through said receiving chamber and said second wrapper folding channel; wrapper folders having reciprocating movements across the path of the first named plunger, said wrapper folders being actuated by said second plunger; means for actuating said second plunger, whereby said wrapper folders are actuated, thereby causing the wrapper to be further folded upon said articles.

3. A packaging machine comprising a magazine for articles, said magazine having movable partitions, means for actuating said movable partitions whereby they are separated sufficient distances apart to permit entry of several of said articles, a wrapper folding channel and a receiving chamber on one side of said magazine, and a reciprocating plunger on the opposite side, a support for a wrapper between said wrapper folding channel, and said magazine, means for actuating said plunger, said means for actuating said movable partition being actuated by said plunger, whereby forward movement of the plunger causes the partitions to be brought closer together, thereby causing said several articles to be forced into a compact bunch, further forward movement of said plunger then causing said articles and wrapper to be forced through said wrapper folding channel, whereby the wrapper is partially folded upon said articles; a second wrapper folding channel in range with said receiving chamber, and a second plunger having reciprocating movements through said receiving chamber and said second wrapper folding channel; wrapper folders having reciprocating movements across the path of the first named plunger, said wrapper folders being actuated by said second plunger; means for actuating said second plunger, whereby said wrapper folders are actuated, thereby causing the wrapper to be further folded upon said articles, further forward movement of said second plunger then causing said partially wrapped articles to be forced into said second wrapper folding channel, thereby causing said wrapper to be completely folded upon said articles; automatic mechanism for

actuating the first named plunger actuating mechanism and said second plunger actuating mechanism; and adjusting means for disconnecting said automatic mechanism, 5 whereby each one of said plunger actuating mechanisms is rendered independently operative by manual means.

5. A packaging machine comprising a receiving chamber and a wrapper folding channel; a reciprocating plunger, a support for a wrapper between said wrapper folding channel and said plunger, and supports for articles between said plunger and said support for a wrapper; means for actuating said plunger, whereby said articles and wrapper are forced through said wrapper folding channel and into said receiving chamber, thereby causing said wrapper to be partially folded upon said articles; a second 10 wrapper folding channel in range with said receiving chamber, and a second plunger having reciprocating movements through said receiving chamber and second wrapper folding channel; certain walls of said receiving chamber having reciprocating movements across the path of said second plunger; wrapper folders having reciprocating movements across the path of the first named plunger, said movable walls and said wrapper folders being actuated by said second plunger; means for actuating said second plunger, whereby said wrapper folders are actuated, thereby causing the wrapper to be further folded upon said partially wrapped 15 articles, further forward movement of said second plunger then causing said movable walls to be actuated, thereby causing said walls to be moved away from the path of said second plunger, whereby said second plunger causes said partially wrapped articles to be forced through said second wrapper folding channel, thereby causing said wrapper to be completely folded upon said articles.

45. 6. A packaging machine comprising a receiving chamber and a wrapper folding channel, a reciprocating plunger, a support for a wrapper between said wrapper folding channel and said plunger, and supports for articles between said plunger and said support for a wrapper; means for actuating said plunger, whereby said articles and wrapper are forced through said wrapper folding channel and into said receiving chamber, thereby causing said wrapper to be partially folded upon said articles; a second wrapper folding channel in range with said receiving chamber, and a second plunger having reciprocating movements 20 through said receiving chamber and second wrapper folding channel, certain walls of said receiving chamber having reciprocating movements across the path of said second plunger wrapper folders having reciprocating movements across the path of the first

named plunger, said wrapper folders being actuated by said second plunger, means for actuating said second plunger, whereby said wrapper folders are actuated, thereby causing the wrapper to be further folded upon 70 said partially wrapped articles, further forward movement of said second plunger then causing said partially wrapped articles to be forced through said second wrapper folding channel thereby causing said wrapper to be 75 completely folded upon said articles.

7. A packaging machine comprising a magazine for articles, said magazine having partitions forming pockets for receiving several of said articles, said magazine having a reciprocating shaker for causing said articles to come to rest between said partitions; a wrapper folding channel and a receiving chamber on one side of said magazine, and a reciprocating plunger on the opposite 80 side, a support for a wrapper between said wrapper folding channel and said magazine; means for actuating said plunger, whereby said articles and wrapper are forced through said wrapper folding channel and into said receiving chamber, thereby causing said wrapper to be partially folded upon said articles; a second wrapper folding channel in range with the first named receiving chamber, and a second plunger having reciprocating movements through the first named receiving chamber and said second wrapper folding channel, wrapper folders having reciprocating movements 85 across the path of the first named plunger, said wrapper folders being actuated by said second plunger, means for actuating said second plunger, whereby said wrapper folders are actuated, thereby causing the wrapper to be further folded upon said partially wrapped 90 articles, further forward movement of said second plunger then causing said wrapper to be completely folded upon said articles; and mechanism connecting said means for actuating said second plunger to said shaker, whereby said reciprocating movements thereof are effected.

8. A packaging machine comprising a magazine for articles, said magazine having partitions forming pockets for receiving several of said articles, said magazine having a reciprocating shaker arranged to cause 120 said articles to come to rest in the pockets formed by said partitions; a wrapper folding channel, a paste applying mechanism and a receiving chamber on one side of said magazine, a reciprocating plunger on the 125 opposite side, a support for a wrapper between said wrapper folding channel and said magazine; a second wrapper folding channel, a second paste applying mechanism, and a receiving chamber in range with the first 130

named receiving chamber, and a second plunger having reciprocating movements through the first named receiving chamber and said second wrapper folding channel; and said second wrapper folding channel; 5 movable wrapper folders which are actuated by said second plunger; a receiving channel in range with said second receiving chamber, and a third plunger having reciprocating movements through said second receiving chamber; means for actuating the 10 first named plunger whereby said articles and wrapper are forced through the first named wrapper folding channel and into the first named receiving chamber thereby causing said wrapper to be partially folded upon said articles, means whereby said means for actuating the first named plunger also actuates the first named paste applying mechanism; means for actuating said second plunger, 15 whereby said wrapper folders are actuated thereby causing the wrapper to be further folded upon said partially wrapped articles, further forward movement of said second plunger then causing said partially wrapped 20 articles to be forced through said second wrapper folding channel and into said second receiving chamber, thereby causing the wrapper to be completely folded upon said articles; means whereby said means for actuating said second plunger also actuates said second paste applying mechanism, and said shaker of said magazine; and mechanism connecting said means for actuating the first named plunger to said third plunger, whereby said third plunger is actuated, 25 thereby causing said wrapped articles to be forced from said second receiving chamber into said receiving channel.

9. A packaging machine comprising a 30 magazine for articles, said magazine having movable partitions, means for actuating said movable partitions whereby they are separated sufficient distances apart to permit entry of several of said articles, a wrapper folding channel, a paste applying mechanism and a receiving chamber on one side of said magazine, a reciprocating plunger on the opposite side, a support for a wrapper between said wrapper folding channel and 35 said magazine, means actuating said plunger, said means for actuating said movable partitions being actuated by said plunger, whereby forward movement of the plunger causes the partitions to be brought closer together, thereby causing said several articles to be forced into a compact bunch, further forward movement of said plunger then causing said articles and wrapper to be forced through said wrapper folding channel and 40 into said receiving chamber, whereby the wrapper is partially folded upon said articles, means whereby said means for actuating said plunger also actuates said paste applying mechanism; a second wrapper folding channel in range with said receiving chamber,

and a second plunger having reciprocating movements through said receiving chamber and said second wrapper folding channel; wrapper folders having reciprocating movements across the path of the first named 70 plunger, said wrapper folders being actuated by said second plunger; means for actuating said second plunger, whereby said wrapper folders are actuated, thereby causing the wrapper to be further folded upon 75 said articles, further forward movement of said second plunger then causing said partially wrapped articles to be forced into said second wrapper folding channel, thereby causing said wrapper to be further folded upon said articles; a second paste applying mechanism in range with parts of said wrapper during travel thereof through said second wrapper folding channel; and means whereby said means for actuating said second plunger also actuates said second paste applying mechanism.

10. A packaging machine comprising a receiving chamber and a wrapper folding channel, a reciprocating plunger, a support 90 for a wrapper between said wrapper folding channel and said plunger, and supports for articles between said plunger and said support for a wrapper, means for actuating said plunger, whereby said articles and 95 wrapper are forced into said wrapper folding channel, thereby causing said wrapper to be partially folded upon said articles; a paste applying mechanism in range with parts of said wrapper during travel thereof 100 through said wrapper folding channel, means whereby said means for actuating said plunger also actuates said paste applying mechanism; further forward movement of said plunger then causing said articles and 105 paste coated parts of the wrapper to be forced through said wrapper folding channel, and into said receiving chamber, thereby causing said paste coated parts of the wrapper to be folded upon the wrapper 110 containing said articles, a second wrapper folding channel in range with said receiving chamber, and a second plunger having reciprocating movements through said receiving chamber and second wrapper folding channels, wrapper folders having reciprocating movements across the path of the first named plunger, said wrapper folders being actuated by said second plunger; 115 means for actuating said second plunger, whereby said wrapper folders are actuated, thereby causing the wrapper to be further folded upon said articles, further forward movement of said second plunger then causing said partially wrapped articles to be forced 120 into said second wrapper folding channel, thereby causing said wrapper to be further folded upon said articles; a second paste applying mechanism in range with parts of said wrapper during travel thereof through 125

130

said second wrapper folding channel; and means whereby said means for actuating said second plunger also actuates said second paste applying mechanism.

- 5 11. A packaging machine comprising a receiving chamber and a wrapper folding channel, a reciprocating plunger, a support for a wrapper between said wrapper folding channel and said plunger, and supports 10 for articles between said plunger and said support for a wrapper, means for actuating said plunger, whereby said articles and wrapper are forced through said wrapper folding channel and into said receiving chamber, thereby causing said wrapper to be 15 partially folded upon said articles; a second wrapper folding channel and receiving chamber in range with the first named receiving chamber, and a second plunger having reciprocating movements through the first named receiving chamber and said second wrapper folding channel; wrapper folders having reciprocating movements across the path of the first named plunger, said 20 wrapper folders being actuated by said second plunger; means for actuating said second plunger, whereby said wrapper folders are actuated, thereby causing the wrapper to be further folded upon said partially 25 wrapped articles, further forward movement of said second plunger then causing said partially wrapped articles to be forced through said second wrapper folding channel and into said second receiving chamber, thereby causing said wrapper to be completely 30 folded upon said articles; a receiving channel in range with said second receiving chamber, a third plunger, having reciprocating movements through said second 35 receiving chamber; and mechanism connecting said third plunger to said means for actuating the first named plunger, whereby said third plunger is actuated, thereby causing said wrapped articles to be forced from 40 said second receiving chamber into said receiving channel.

12. A packaging machine comprising a magazine for articles, a wrapper folding channel and a receiving chamber on one side 50 of said magazine, and a reciprocating plunger on the opposite side, a support for a wrapper between said wrapper folding channel and said magazine, means for actuating said plunger whereby forward movement 55 thereof causes said articles and wrapper to be forced through said wrapper folding channel and into said receiving chamber, whereby the wrapper is partially folded upon said articles; a second plunger having reciprocating movements through said receiving chamber; wrapper folders having reciprocating movements across the path of the first named plunger; said receiving 60 chamber provided with side walls having reciprocating movements across the path of said plunger, said receiving chamber, whereby the wrapper is partially folded upon said articles; a second plunger having reciprocating movements through said receiving chamber; wrapper folders having reciprocating movements across the path of the first named plunger; said receiving 65 chamber provided with side walls having reciprocating movements across the path of said plunger, said receiving chamber, whereby the wrapper is partially folded upon said articles.

the second plunger; said wrapper folders and said side walls of the receiving chamber being actuated by said second plunger; means for actuating said second plunger, whereby said side walls are moved out of range with said second plunger, and whereby said wrapper folders are actuated, thereby causing the wrapper to be further folded upon said articles, further forward movement of said second plunger then causing 75 said articles and wrapper to be moved out of said receiving chamber.

13. A packaging machine, comprising a wrapper folding channel and a receiving chamber; means whereby a series of articles and a wrapper can be moved through said wrapper folding channel and into said receiving chamber, whereby the wrapper is partially folded upon said articles; a plunger having reciprocating movements through 80 said receiving chamber; wrapper folders having reciprocating movements into and out of said wrapper folding channel; said receiving chamber provided with side walls having reciprocating movements across the 85 path of said plunger, said wrapper folders and said side walls of the receiving chamber being actuated by said plunger; means for actuating said plunger whereby said side walls are moved out of range with the plunger, and whereby said wrapper folders are actuated thereby causing the wrapper to be further folded upon said articles, further forward movement of said second plunger then causing said articles and wrapper to be 90 moved out of said receiving chamber.

14. A packaging machine, comprising a wrapper folding channel and a receiving chamber; means whereby a series of articles and a wrapper can be moved through 105 said wrapper folding channel and into said receiving chamber, whereby the wrapper is partially folded upon said articles; a second wrapper folding channel in range with said receiving chamber; a plunger having reciprocating movements through said receiving chamber and said second wrapper folding channel; said receiving chamber provided with side walls having reciprocating movements across the path of said plunger, said 110 side walls being actuated by said plunger; means for actuating said plunger, whereby said side walls are moved out of range with said plunger, further forward movement of said plunger then causing said partially 115 wrapped articles to be forced through said second wrapper folding channel, thereby causing said wrapper to be completely folded upon said articles.

15. A packaging machine, comprising a 125 wrapper folding channel and a receiving chamber; means whereby a series of articles and a wrapper can be moved through said wrapper folding channel and into said receiving chamber, whereby the wrapper is 130

partially folded upon said articles; a second wrapper folding channel in range with said receiving chamber, consisting of upper and lower plates and a side folder; said 5 upper plate having a folder which extends vertically downward in line with the inner end of said side folder and having its lower edge inclined downward at an angle of about 30° from said upper plate; the inner end of 10 said side folder extending toward said downwardly extending folder and shaped so that a narrow inclined slot is left between said side folder and the inclined edge of said downwardly extending folder; said lower 15 plate having a folder which extends vertically upward in line with said downwardly extending folder and having its upper edge inclined upward at an angle of about 30° from said lower plate; a vertical plate in 20 line with said downwardly extending folder

extending toward said upwardly extending folder and shaped so that a narrow inclined slot is left between said vertical plate and the inclined edge of said upwardly extending folder; and means whereby said articles 25 and partially folded wrapper can be moved through said second wrapper folding channel, whereby the wrapper is completely folded upon the article, said extension of said side folder, said downwardly extending 30 folder, and said upwardly extending folder serving to hold said articles in place while the wrapper is being folded.

Signed at New York city in the county of Queens and State of New York this 8th day 35 of May A. D. 1914.
